TENSIONING MECHANISM FOR WINDING MACHINES

James E. Bancroft, Jamaica, N. Y., assignor to Allied Control Company, Inc., New York, N. Y., a corporation of New York

Application December 24, 1952, Serial No. 327,777

7 Claims. (Cl. 242—45)

This invention relates to tensioning mechanism for use in winding and reeling machines.

In my co-pending application Ser. No. 162,491, filed May 17, 1950, now Patent No. 2,672,298, I disclose a coil winding machine for winding magnet coils such as are used in relays and the like. Such machines wind a plurality of coils simultaneously, magnet wire being drawn from supply spools equal in number to the number of coils being wound. The tension on all wires should be equal for uniformity of product and the tensioning mechanism of the present invention is especially adapted for use in such machines but, as will be obvious, its use, is not limited thereto.

The principal object of the invention is to provide improved tensioning means giving winding machines increased versatility.

Another object is to provide tensioning mechanism adaptable for use in the winding or spooling of wire or other filamentary materials, ribbons, and the like, capable of a wide range of tension adjustments.

A further object is to provide tensioning means for use with a plurality of supply spools wherein the tension of the wire or other material from all spools may be simultaneously adjusted by a single operation.

Another object is to provide improved braking mechanism for use in tensioning means having a wear compensation adjustment which is independent of the tension adjustments.

Other objects and advantages of the invention will in part appear and in part will be obvious from the following description of the present embodiment of the invention, 45 taken in conjunction with the drawings in which:

Fig. 1 is a side elevation of a single tensioning unit shown in its relation to the supply spool and coil winding mechanism mounted on a supporting frame, and attached to tension adjusting mechanism, taken on the line 1—1 of Fig. 3;

Fig. 2 is an enlarged elevation, partly in cross-section, of the dual tensioning spring and associated parts;

Fig. 3 is a partial rear elevation showing the means for simultaneously adjusting a plurality of tension springs;

Fig. 4 is a front elevation of the braking unit and spool holder;

Fig. 5 is a side elevation thereof;

Fig. 6 is a detail plan taken on the line 6—6 of Fig. 4; and

Fig. 7 is a fragmentary detail of one end of the tension adjusting bar showing the means for holding the nuts in the adjusting bar, taken on the line 7—7 of Fig. 3.

Referring to Fig. 1, the tensioning devices may be supported on a pipe rack having vertical pipes 10, supported in proper relation to the winding machine, to which are attached by clamps 11, the horizontal pipes 12 and 13. Only one pipe 13 is shown but it will be understood that several may be used, supporting spools at different levels.

The tensioning mechanism comprises an upper or lever arm portion generally indicated at 14 secured to pipe 12; and a lower or braking portion generally indicated

2

at 15 secured to pipe 13, connected by pull rod 16. The upper portion 14 is supported from a clamp 18 having a downwardly extending yoke 19 which pivotally supports a split block 20 in which is clamped a tensioning arm 21 of heavy spring wire or the like carrying pulleys 22 and 24. Arm 21 may be rigid if desired, or somewhat flexible. Pull rod 16 is pivotally attached to block 20 at a point 25 closely behind the pivotal point 26 for block 20. Arm 21 extends to the rear of the supporting pipe frame 10 and carries at its rear end a connecting block 28 to which is attached the upper end of the dual tension spring unit, hereinafter described, which pulls downwardly on the rear end of the arm 21 thus urging the front end of the arm and the pulleys carried thereby upwardly against the pull exerted thereon by the wire 30.

The coil or the like being wound is shown at 31, the wire extending therefrom upwardly around a roller 32, over the pulleys 24 and 22, and thence downwardly to the supply spool 34. The portion of arm 21 between the 20 pulleys is shown as foreshortened but in actual practice the length of this arm forwardly of pivot 26 will be about three times as long as the rear portion behind that pivot. The parts as shown in the drawing are in the position they would assume when there is substantially no tension on wire 30, in which position the rear end of arm 21 rests on a cross-bar 35. As soon as coil winding begins, the front end of arm 21 will be pulled down and the arm will operate about a median position which may, for example, be horizontal.

Spool 34 is held on a spindle 36 between a coil spring 38 and a slide catch 39, rotation of the spool relative to the spindle being prevented by a finger 40 which is inserted in a hole in the end of the spool. Spindle 36 has a splined portion 41 (Fig. 5) which has a press fit in a 35 cylindrical brake drum 42. The spindle is mounted in ball bearings 44, 45 in the hub 46 of a supporting clamp 48 by which it is fixed to a pipe 13. Fixed in a boss 49, also forming part of the clamp, is a forwardly extending bearing pin 50 on which are rotatably mounted a brake beam 51 and a yoke-shaped brake shoe supporting arm 52.

Referring to Figs. 4 and 6, a compression spring 54 is interposed between the cup-shaped ends of said beam and said arm as shown at the left in the drawing, and the beam 51 carries a wear-compensation adjusting screw 55 which bears against the opposite end 56 of the arm 52 and acts in opposition to spring 54. Screw 55 is held against rotation by a spring wire clip 58. Pivotally supported on a pin 59 between the sides of the arm 52 is a brake shoe 60 having a compressible lining 61 of felt or the like which bears against the brake drum. In the central portion of brake beam 51 is a cup 62 which holds one end of a compression coil spring 64, the other end of which rests in a cap 65 freely rotatable on the end of a thumb screw 66 by which spring 64 may be adjustably compressed to urge the brake shoe against the brake drum. Screw 66 is threaded through a side extension 68 of clamp 48. Pull rod 16 extends through the end of 60 brake beam 51 and on the under side thereof is provided with a spring nut 69 for engagement with the under side of the beam. Thus when pull rod 16 is raised beyond a predetermined point it moves brake beam 51 counterclockwise about its pivot 50 in opposition to the pressure of spring 64 and reduces the pressure on brake shoe 60, permitting the spool to turn more freely and reducing the tension on wire 30. This motion is very slight. When there is no tension on the wire, nut 69 on pull rod 16 is adjusted so as to be out of contact with brake beam 51 and the brake pressure will depend solely on the adjusted tension of spring 64.

Referring to Figs. 1, 2 and 3, the dual tension spring unit to which the rear end of arm 21 is connected is con-

structed as follows. An upper, relatively stiff, helical coil spring 70 is connected to a lower, relatively light helical coil spring 71 by a fitting 72 having a bore 74. This fitting is threaded at opposite ends, preferably with square threads, on which the ends of the two springs may be screwed. A similar single ended fitting 75, also having a bore, is screwed into the lower end of spring 71. Inside of spring 70 is a tube 76 and an end plug 78 which rests on top of the tube and engages the underside of the end loop 79 of the spring. Passing upwardly through the bores of fittings 75 and 72 and into the tube 76 is a draw-rod 80 having a stop-member or head 81 adapted to engage the upper face of fitting 72. The lower end of the rod 80 passes through a threaded fitting 82 (Fig. 3) which is held by a lock nut 84 in an inverted U-shaped tension adjusting bar 85 which extends across the back of frame 10. A collar 86 on rod 80 secures it to bar 85. Fitting 75 has a set screw 87 by which its position on rod 80 is fixed.

In each end of the bar 85 is a nut 90 held in place by a cage 91 welded inside of the bar (Fig. 7) the nuts being threaded on elevating screws 92 which pass through holes in the bar and the cages. The upper ends of the screws rotate in bearings 94 and the lower ends in bearings 95. Screws 92 are connected at their lower ends with a cross shaft 96 through bevel gears 98 so that the two screws can be rotated simultaneously by a crank 99. To permit rapid adjustment of the bar 85 to a predetermined position the bar may carry a pointer 100 which reads against a scale 101 attached to a stationary part of the frame, such as one of the pipes 10. Thus the tension on all wires may be changed simultaneously by turning crank 99.

One of the important aspects of the invention is the dual tension spring unit of Fig. 2, the construction of which has been generally described above and which will now be explained in more detail. It is this unit, in conjunction with the tension adjusting bar 85 or other means for varying the position of the anchored end of draw-rod 80, which provides the desirable wide range of possible tension adjustments. Heretofore when a great change in tension has been necessitated, for example by a shift from very fine to very heavy wire, it has been usual to substitute heavier for lighter springs, since, for the proper control of tension, a certain amount of deflection of the tension arms 21 is required which cannot be obtained with a light pull on a short stiff spring which would give such deflection only under a load in excess of that desired. Another but impractical way of providing a great change in tension would be to use long springs which would have to be stretched through a great distance. By using the relatively short dual spring arrangement the advantages of long springs may be had without their disadvantages.

To illustrate the principle involved, let it be assumed that the light lower spring 71 is of such size and length as to have a spring rate of one inch of extension per pound of pull. This spring is utilized, for example, to provide a total tension range from zero to four pounds. A four pound pull elongates it to the point where the head 81 on draw-rod 80 engages the fitting 72 so that any further pull on the unit through arm 21 is taken up by the upper heavier spring 70. The latter spring, for example, will have a spring rate of one inch of extension for two pounds of pull and it is placed under an initial tension, by means of tube 76 and plug 78 which are inserted in it for this purpose. This pretensioning is accomplished as follows. With the aid of suitable tension measuring devices a length of spring is determined which gives the desired spring rate, an allowance of the proper number of additional turns is made for attachment to fitting 72 and the spring is cut off. A tube and plug having a combined length sufficient to place spring 70 under a tension of four pounds when the spring is coupled to fitting 72 is inserted in the spring and the fitting

screwed into the spring end. The plugs 78 serve a dual purpose. Being solid they provide durable stops for engagement with the looped spring ends, which occurs with a blow when a wire breaks. Secondly, they can be made in a variety of lengths thus enabling tubes of uniform length to be used, the pretensioning adjustment being made by using the proper length of plug.

It is thus possible to make up a set of dual spring tension units all of which have the same operating characteristics. It then becomes possible to change uniformly the tension of all the wires on the machine by movement of the adjusting bar 85 which stretches or relaxes all of the spring units to the same extent. By means of a calibrated scale such as 101 the tension of all units on the machine can be quickly set for any given wire size, it having been determined empirically what tension is best for each size.

Another important aspect of the invention relates to the construction and adjustment of the brake mechanism of Figs. 4, 5 and 6. All brake pressures, on a machine assumed to have a plurality of tensioners, are initially set by compression of the springs 64 to be uniform, for example five pounds as measured at the brake shoe pivots 59 with a suitable gauge. The spring nuts 69 are adjusted to permit all of the pulley arms 21 to float, under any given wire tension, in approximately the same plane, for example horizontally, or in any other desired position intermediate their extreme positions, and to act on the brake beams 51 if their front ends move below that plane. As the machine is run the brakes are never full on or full off but maintain just enough friction on the brake drums to maintain the desired tension on the wires. Increased wire tension pulls arms 21 down and reduces this friction and vice versa.

Inevitably there is wear on the brake linings tending to reduce the wire tension and such wear will cause the front ends of arms 21 to rise. If this condition were to be repeatedly corrected by moving spring nut 69, the end result would be a lengthening of spring 64 so that the maximum brake pressures determined by springs 64 would cease to be uniform. To avoid this, the above described separate wear adjustment is provided in the screw 55 acting on arm 52 which sets the brake shoe closer to the drum without changing the compression of spring 64. Hence, once adjusted, springs 64 and nuts 69 need not be touched again. It is easily determined when wear adjustment is required merely by watching the position of arms 21 as the machine is in operation. When one of them begins to rise out of the normal median plane of operation its corresponding screw 55 is merely turned down sufficiently to bring it back.

Summing up the operation of the tensioning devices above described, when consumption of wire 30 begins, as by winding it on a coil, the supply spool is held stationary by the brake until arm 21 rotates on its pivot to deflect the dual spring unit by a predetermined amount, which depends on the position of the tension adjusting bar 85. This pulls arm 21 down to its operating position. The tension is maintained by the action of pull rod 16 on the brake beam 51 in reducing brake pressure as arm 21 moves below its operating position. This releases more wire from the spool and arm 21 returns, again increasing brake pressure and maintaining tension substantially uniform.

The term "wire" as used in the claims is to be deemed inclusive of other filamentary materials comprising a single strand or multiple strands and other spoolable materials such as ribbon or tape with which tension devices are useful, the invention claimed being wholly independent of the material being handled.

It is to be understood that the novel features of the mechanism as above described are not restricted in their use to the particular combination illustrated but may be used in combination with other parts or elements performing like functions. As herein described they oper-

ate together, however, to produce a particularly advantageous single result, namely a smooth control of the tension of a plurality of wires or the like permitting a number of coils or spools to be uniformly wound. Many details of the construction described to illustrate the invention may, of course, be varied without departure from the invention as defined in the appended claims.

What is claimed is:

1. In a machine for simultaneously winding a plurality of coils, in combination, means for holding a plurality of spools of wire to be wound into coils, separate braking means acting to tension the wire drawn from each of said spools, pivoted arms having guide means over which each of the wires passes coupled with said braking means, a movable tension adjusting bar, tensioning springs attached at one end to each of said arms and at their other ends to said bar, and means for adjusting the position of said bar to simultaneously adjust the tension applied by said springs to said arms.

2. In a machine for simultaneously winding a plurality of coils, in combination, a plurality of spindles adapted to hold spools of wire to be wound into coils, separate braking means associated with each of said spindles and acting to tension the wire drawn from said spools, a plurality of pivoted arms having guide means over which the wires individually pass, means coupling said arms with said braking means, a movable tension adjusting bar, means for adjusting the position of said bar, and tension springs anchored to said bar and connected to each of said arms, whereby the tension on all arms can be uniformly and simultaneously varied by moving said bar.

3. In a machine for simultaneously winding a plurality of coils, in combination, means for holding a plurality of spools of wire to be wound into coils, separate braking means acting to tension the wire drawn from each of said spools, a plurality of pivoted arms having guide means over which each of the wires passes coupled with said braking means, a movable tension adjusting bar, tensioning springs attached at one end to each of said arms and at their other ends to said bar, parallel rotatable screws having threaded connections with said bar, and means for simultaneously rotating said screws to position said bar and simultaneously adjust the tension of said springs.

4. In brake mechanism of the type comprising a brake drum, a brake shoe in frictional engagement therewith and subject to wear, a pivoted brake beam, and a spring acting on said beam to apply braking pressure to said shoe; the improvement which comprises the provision of an arm separate from said beam, said shoe being carried by said arm, means for pivotally supporting said arm for movement relative to said beam, and adjustable means for transmitting movement of said beam to said arm whereby their relative operating positions can be varied, whereby wear of said shoe may be compensated for by said adjustable means without alteration of the braking pressure applied by said spring.

5. The mechanism of claim 4 wherein said arm and said beam are mounted on a common pivot intermediate their ends, a compression spring is interposed between said arm and said beam on one side of said pivot, to separate their adjacent ends, said shoe being supported by said arm on the other side of said pivot, and said adjustable means is also disposed on said other side of said pivot and adapted to act in opposition to the force of said compression spring to change the relative positions of said arm and beam.

6. The mechanism of claim 5 wherein said adjustable means is a screw.

7. A dual spring tension unit comprising a light spring and a heavier spring each of helical coil form arranged in end to end relationship, a coupling having a bore and connected with the adjacent ends of the two springs, a fitting having a bore attached to the other end of the light spring, a draw rod passing through the bores in said fitting and said coupling, means for fixing the position of said fitting on said rod, a stop member on said rod adapted to limit the extension of the light spring by engagement with said coupling and thereby to transmit the pull on the rod to the heavier spring, and means within the heavier spring pretensioning the heavier spring to the tension of the light spring at its maximum extension as determined by said stop member; said last mentioned means comprising a rigid tube adapted at one end to engage said coupling, and a plug engaging the other end of said tube and the end of said heavier spring, the bore of said tube freely receiving said stop member, and the combined lengths of said tube and said plug being such as to maintain said heavier spring in a slightly extended position and under the tension exerted by the light spring at its maximum extension.
